UNITED STATES PATENT OFFICE.

PHILIP E. BLUM, OF DANSVILLE, NEW YORK.

DESIGN FOR A SLIPPER.

51,535.

Specification for Design.

Patented Dec. 4, 1917.

Application filed October 11, 1917. Serial No. 196,083. Term of patent 7 years.

To all whom it may concern:

Be it known that I, PHILIP E. BLUM, a citizen of the United States, residing at Dansville, in the county of Livingston and State of New York, have invented a new, original, and ornamental Design for Slippers, of which the following is a specification, reference being had to the accompanying drawing, forming part thereof.

The figure is a perspective view of a slipper, showing my new design.

I claim:

The ornamental design for a slipper, as shown.

PHILIP E. BLUM.
